UNITED STATES PATENT OFFICE.

WILLIAM G. WEHR, OF EAST CLEVELAND, OHIO, ASSIGNOR TO THE CLEVELAND CRANE
AND ENGINEERING COMPANY, OF WICKLIFFE, OHIO, A CORPORATION OF OHIO,

CRANE.

Application filed September 4, 1923. Serial No. 660,754.

To all whom it may concern:

Be it known that I, WILLIAM G. WEHR, a citizen of the United States, residing at East Cleveland, in the county of Cuyahoga and State of Ohio, have invented a certain new and useful Improvement in Cranes, of which the following is a full, clear, and exact description.

The present invention relates to overhead traveling cranes of the type commonly used for lifting, transferring and depositing relatively heavy articles from any particular point or location to any other desired location within such rectangular shaped space as a crane may be designed to cover, and likewise having bridge, trolley and runway members.

The runways of the usual crane are arranged parallel to each other and extend longitudinally of the working space it is desired to cover by the crane one located on each side of such space. These runways form the support for stationary track surfaces which extend from end to end thereof, and lying in the same horizontal plane at a fixed elevation, they constitute the support for flanged truck wheels with which the bridge is provided and which are adapted to travel thereon.

30 The bridge is of a length to span across the space between said runway tracks with its truck wheels arranged so as to retain (theoretically) its longitudinal axis at right angles therewith while it is propelled laterally along the same.

35 The trolley which is supported by the bridge is provided with flanged truck wheels for its support and adapted to travel upon longitudinal track surfaces with which the bridge is provided and which extend from end to end thereof, said trolley being thus enabled to move back and forth across the space covered by the bridge. The trolley constitutes the member forming the support

40 for hoisting apparatus for raising and lowering whatever weight or article the crane is designed to carry, the same being usually suspended beneath it.

45 The operation of the crane thus being as follows: When an article is hoisted so as to be clear from the floor level beneath it and of any objects lying thereon, by moving the bridge along the runway tracks separately or simultaneously said article can be carried

50 to and deposited in any position within the

space that is spanned by the bridge and is subtended by the runway tracks. Such movements usually are subject to independent control and they are also effected either by the application of manual power or of 60 electrically driven motors acting intermittently, each being separately subject to manual control. Said power applications are commonly effected through the medium of wheel gearing having connection with the 65 drum of the hoisting apparatus and with the wheels upon which the trolley and the bridge members are mounted.

Due to the fact that the flanges of those wheels which support the bridge are unable 70 usually to exercise an effective control to secure such concerted movements of the opposite ends of the bridge, as to maintain it securely in its proper and square relationship with the runway tracks, on account of 75 the relative shortness of the wheel base of its end trucks as compared with the length of span between said tracks, it is common to rigidly connect corresponding wheels at 80 said opposite ends of the bridge by means of shafting extending lengthwise of the bridge between the end trucks. Even under these conditions the bridge portion of the crane must at times be "squared" with respect to 85 the runways.

In order that cranes of the above class may possess requisite strength and stability they are necessarily heavy and as heretofore constructed much friction is consequently 90 developed in the action of those parts by which their horizontal movements are effected, and in order that such movements may be rapidly executed, relatively powerful motors must be used and where manual power only can be afforded, much severe 95 labor is involved and the movements are of necessity slow and unsatisfactory and consequently their use is prohibited in many lines.

100 It is therefore the object of the present invention to materially simplify the construction of the crane, to materially lower the cost of its construction and maintenance, and to so reduce the friction in those parts 105 by whose action the horizontal movement of the bridge and the trolley are effected, that when an article is lifted so as to be clear of all obstructions, it may be moved in any direction by the application of a slight horizontal pressure exerted against it or the 110

into an annular opening in the truck body 12.

At the upper ends of each wheel frame 23, a pair of oppositely disposed track wheels 25 are rotatably supported on pins 26 by 5 anti-friction bearings. Combined radial and end thrust bearings designated as a whole by the reference character 27 are preferably employed.

It is important to the attainment of the 10 object of this invention, and to reduce the force necessary to move the crane along its runway, that friction of the wheels 25 on their bearings be as small as possible, and for that reason suitable anti-friction bearings 15 of the ball or roller type are utilized. Likewise it is important that rubbing and therefore friction between the wheels and the trackways be avoided.

The two pairs of wheels engage and ride 20 over the two lower flanges 14^a of each T rail trackway 14. The crane runway therefore consists of two double trackways constituting in effect four rails or surfaces, two for one end of the crane and two for the 25 other.

It is to be noted in this connection that the treads of the wheels 25 are beveled and that the upper surfaces of the flanges over which the wheels run are beveled or tapered 30 downwardly from the web of the rail. This feature is important to the attainment of the object of this invention for in co-operation with other features, it maintains the cross member of the crane square with respect 35 to the runways and prevents skewing of the crane when force is applied near one end thereof (as when the trolley is near said end) to move the crane along its runway. The bevel of the wheel treads and the taper 40 of the trackways have this effect for the reason that any skewing or rotating of the crane about one end requires that part of the wheels run up the incline of the trackways but the weight of the crane whether 45 loaded or not tends to prevent this, and there is therefore a constant tendency for the crane to remain in its lowest possible position and for the beveled wheel and trackway surfaces to oppose the lifting of the 50 weight of the crane as would ensue if the crane should skew or move out of square with respect to the runways.

I do not regard it as essential that both the treads of the wheels and the wheel en- 55 gaging flange of the rails be inclined or tapered, but it is important that one or the other be tapered, and in the claims this feature is defined by the expression "tapered or inclined contact".

60 The wheels 25 as shown are provided with flanges 25^a but these are not necessary to maintain the wheels properly on the trackways, and, in fact, under ordinary conditions the flanges of the wheels do not bear 65 against the edges of the flanges 14^a forming

the trackways and, indeed, this engagement is not desired, and in my construction is avoided, for as already stated it is important that the friction and resistance to movement be minimized.

70 Another feature which I believe to be essential to the attainment of the result just stated, i. e. the prevention of friction and of a rubbing action between the flanges of the trackways and of the wheels and for the prevention of skewing of the crane when force to move it is applied near one end, is the flexible suspension of the trackway rails 14. It will be observed that the rails are flexibly suspended through the medium of suspending members or rods 28 which allow the rails to move laterally slightly. By this expedient slight irregularities in the alignment in the rails 14 is compensated for, for the reason that the tapered wheels 80 and trackways and the necessity of the wheels lifting the weight of the crane and its load (if it is loaded) by the movement of the wheels up the inclined surfaces of the trackways will cause such a lateral shifting 85 of the rails as to compensate for irregularities in alignment, the net effect being to keep the wheels and trackways "centered" and preventing dragging of the flanges of the 90 wheels against the outer edges of the trackways.

95 The wheels therefore ride onto the lower portions of the flanges of the trackways so that the crane will be kept in its lowest possible position. Because of the bevel or taper 100 of the wheels and of the flanges of the trackways or of the "inclined contact", also the flexible suspension of the rails which allows the rails to adjust themselves by a slight lateral movement to the wheels, also the rigid connection between the cross member of the crane and the end trucks, also the low frictional resistance to movement of the crane, and possibly also other features of this combination including the swiveling of the wheel frames on the truck bodies, the crane will 105 remain in its lowest position and will not twist but will remain square or at right angles to the trackways when force is applied 110 near one end of the crane to move it along its runway. In this connection it is to be noted that no shafting need be employed to 115 connect opposite wheels of the end trucks to cause them to act or move in concert.

120 Therefore, even though the trolley is near one end of the cross member of the frame and though it may be supporting its maximum load, the operator by pushing or pulling on the rigid member 21 can cause the crane to travel along its runway and he can 125 do this without the necessity of his applying a great deal of force.

130 Therefore the necessity of first moving the trolley to the center of the cross member of the crane is entirely avoided and loads

can be transmitted from one point to a pre-determined other point much more quickly than heretofore, saving time and labor and therefore greatly improving the efficiency of the crane.

In fact, with my invention practice has shown that not only can the crane be moved along the runway regardless of where the trolley may be located on the cross member of the crane, but if the operator applies the force in the right direction he can at the same time cause the crane to be moved along the runway and the trolley to be moved along the cross member of the crane, thus saving time in transferring a load from one point to another selected point.

While I have shown the preferred construction with numerous important features combined in a novel way or producing a new combination useful for the attainment of the important results or advantages explained above, I do not desire to be confined to the exact construction shown or to a construction combining all the features specifically explained above, but I aim in my claims to cover all modifications which do not involve a departure from the spirit and scope of my invention in its broadest aspect.

Having described my invention, I claim:

1. The combination with a crane runway consisting of two spaced tracks flexibly suspended so as to be capable of limited lateral movement, of a crane movable manually along the runway and having a manually movable trolley, said crane comprising a cross member having end trucks rigidly secured thereto, each truck being provided with wheels engaging the tracks on opposite sides of the cross member, whereby they tend to maintain the crane square with respect to the runway, and the crane may be moved along the runway by applying force to the trolley regardless of the position of the trolley on the cross member of the crane.

2. The combination with a crane runway consisting of spaced tracks flexibly suspended so as to be capable of limited lateral movement, of a crane movable manually along the runway and having a manually movable trolley, said crane comprising a cross member or bridge having end trucks extending crosswise of and rigidly secured to the ends of the cross member and provided on opposite sides of the cross member with track engaging wheels, the treads of the wheels and the wheel engaging surfaces of the tracks having inclined or tapered contact whereby they tend to maintain the crane square with respect to the runway, and the crane may be moved along the runway by applying force to the trolley regardless of the position of the trolley on the cross member of the crane.

3. The combination with a crane runway consisting of two spaced double trackways

flexibly suspended so as to be capable of limited lateral movement, of a crane adapted to be moved manually along the runway and having a manually movable trolley, said crane comprising a cross member having end trucks rigidly secured to its ends, the trucks having on opposite sides of the cross member, pairs of free running wheels engaging the double trackways, the wheels and trackways having tapered or inclined contact whereby the crane is automatically maintained square with respect to the runway, and the crane may be moved along the runway by force applied to the trolley regardless of the position of the trolley on the cross member of the crane.

4. The combination with a crane runway consisting of two rails, each having oppositely extending flanges, the rails being flexibly suspended, of a crane adapted to be moved manually along the runway and having a manually movable trolley, said crane comprising a cross member provided at its ends with end trucks rigidly secured thereto, the trucks each having two pairs of free running wheels engaging the opposite flanges of one of the rails, the treads of the wheels and the upper surfaces of the rail flanges having inclined or tapered contact whereby the latter maintains the crane square with respect to the runway, and the crane may be moved along the runway by applying force to the trolley regardless of its position on the cross member of the crane.

5. The combination with a crane runway consisting of two spaced rails, each having a pair of oppositely extending flanges with tapered upper surfaces, the rails being flexibly suspended so as to be capable of limited lateral movement, of a crane adapted to be moved manually along the runway and having a manually movable trolley carrying a hoist, the crane comprising a cross member and a pair of trucks at the ends thereof, each composed of a truck body arranged transversely of the cross member and rigidly secured thereto, said truck being provided on opposite sides of the cross member with wheel frames having free running wheels on opposite sides of one of the rails and having treads engaging the tapered rail flanges.

6. The combination with a crane runway consisting of two spaced rails, each having a pair of oppositely extending flanges with tapered upper surfaces, the rails being flexibly suspended so as to be capable of limited lateral movement, of a crane adapted to be moved manually along the runway and having a manually movable trolley carrying a hoist, the crane comprising a cross member and a pair of trucks at the ends thereof, each composed of a truck body arranged transversely of the cross member and provided on opposite sides of the latter with wheel frames having wheels on opposite

sides of one of the rails and having treads engaging the tapered rail flanges, the truck bodies being rigidly secured to the cross member of the crane and the wheel frames 5 having a pivoted or swivel connection with the truck bodies.

7. The combination with a crane runway consisting of two spaced tracks flexibly suspended so as to be capable of limited lateral movement, of a crane movable manually along the runway and having a manually movable trolley provided with a hoist, the crane comprising a bridge having end trucks rigidly secured to the ends thereof, the 10 trucks having free running wheels engaging the tracks and provided with anti-friction bearings, said wheels and tracks having a tapered or inclined contact whereby they tend to maintain the crane square with respect to the runway and the crane may be moved along the runway by applying force to the trolley regardless of the position of the trolley on the bridge.

8. The combination with a crane runway consisting of two spaced tracks flexibly suspended so as to be capable of limited lateral movement, of a crane movable along the runway and having a trolley with a hoist, the crane comprising a bridge having rigidly secured to the ends thereof trucks each provided with wheels engaging the tracks on opposite sides of the cross member, the trolley having a rigid downwardly extending member to which force may be applied 30 to move the trolley along the bridge and to move the crane along the runway regardless of the position of the trolley on the bridge.

9. The combination with a crane runway consisting of two spaced rails, each having a pair of oppositely extending flanges, the rails being flexibly suspended so as to be capable of limited lateral movement, of a crane adapted to be moved manually along 40 the runway and having a manually movable trolley carrying a hoist, the crane comprising a cross member and a pair of trucks at the ends thereof, each composed of a truck body arranged transversely of the cross member and rigidly secured thereto and provided on opposite sides of the latter with wheel frames having wheels on opposite

sides of one of the rails and having treads engaging the opposite rail flanges, the trolley having a rigid downwardly extending member to which force is applied to move the trolley along the cross member of the crane and to move the crane along the runway regardless of the position of the trolley on the cross member.

10. The combination with a crane runway consisting of two spaced rails, each having a pair of oppositely extending flanges, of a crane adapted to be moved manually along the runway and having a manually movable trolley carrying a hoist, the crane comprising a cross member and a pair of trucks at the ends thereof, each composed of a truck body arranged transversely of the cross member and provided on opposite sides of 60 the latter with wheel frames having wheels on opposite sides of one of the rails with treads engaging the rail flanges, each truck body being rigidly secured to the cross member of the crane and the wheel frames having a swivel connection with the truck bodies.

11. The combination with a crane runway consisting of two spaced parallel track rails, each having supporting flanges extending 80 along opposite sides thereof, of a crane comprising a cross member bridging the space between the tracks and provided with end trucks extending crosswise thereof having free running supporting wheels arranged in pairs on opposite sides of the cross member with the wheels of each pair traveling upon opposite flanges of the rail, whereby the cross member is maintained square with respect to the runway and may be moved along 85 the runway by a thrust exerted anywhere along the length thereof, and a freely movable hoist carrying trolley mounted to travel along the runway and adapted to be shifted by a thrust exerted manually thereon where by an operator walking along the ground may by pushing or pulling on the trolley cause a combined movement of the trolley and cross member such that the travel of the trolley with respect to the ground is in the 90 direction of thrust.

In testimony whereof, I hereunto affix my signature.

WILLIAM G. WEHR.
